UNITED STATES PATENT OFFICE.

JOE J. WIGIERT, OF BREMOND, TEXAS, ASSIGNOR OF ONE-HALF TO STASH WIGIERT,
OF BREMOND, TEXAS.

COMBINED SWORD AND PISTOL.

1,239,065.

Specification of Letters Patent.

Patented Sept. 4, 1917.

Application filed June 11, 1917. Serial No. 174,026.

To all whom it may concern:

Be it known that I, JOE J. WIGIERT, a citizen of the United States, residing at Bremond, in the county of Robertson and State 5 of Texas, have invented certain new and useful Improvements in Combined Swords and Pistols, of which the following is a specification.

The primary object of the present invention is to provide a combined sword and pistol wherein the pistol is supported by the sword blade adjacent the handle portion thereof and with the stock of the pistol rigidly mounted and providing a structure that 15 is capable of permitting the barrel portion of the pistol to be broken down or moved relatively to the stock to facilitate emptying of the pistol barrel.

A further object of the invention is to 20 provide a combined sword and pistol structure in which the pistol is supported adjacent the sword handle, and wherein the sword handle guard is adjustable relative to the sword and pistol whereby the same may 25 be moved to a position spaced from the pistol handle or stock to facilitate the use of the pistol.

With these general objects in view and others that will appear as the nature of the 30 invention is better understood, the same consists in the novel construction, combination and arrangement of parts hereinafter more fully described, illustrated in the accompanying drawings, and then claimed.

25 In the drawings forming a part of this application, and in which like designating characters refer to corresponding parts throughout the several views:—

Figure 1 is a side elevational view of a 40 combined sword and pistol constructed in accordance with the present invention, the pistol barrel being shown as broken down by dotted lines while the sword handle guard is also shown in a dotted line position when the pistol is to be used.

Fig. 2 is a top plan view of the same.

Fig. 3 is a vertical sectional view taken 50 on line III—III of Fig. 1 showing the bracket for supporting the barrel portion of the pistol.

Fig. 4 is a cross sectional view taken on line IV—IV of Fig. 1 showing the method of supporting the pistol stock, and,

Fig. 5 is a cross sectional view taken on 55 line V—V of Fig. 1 showing the sword han-

dle guard in upright position in full lines and in lowered position in dotted lines with a mechanism for holding the same in either position.

Referring more in detail to the accompanying drawing, the reference numeral 10 designates the blade portion of a sword of any preferred design and having a handle 11 upon one end thereof, upon which is adjustably mounted a guard 12. As shown 60 in Fig. 1, the guard is of substantial U-shape, having at its outer end a ring portion 13 rotatably seated in a corresponding circumferential groove provided in the outer end of the handle 11 while the inner end 65 of the guard 12 is provided with a similar ring 14 journaled in a corresponding groove formed in the inner end of the handle. As clearly shown in Figs. 1 and 5, one side 70 of the ring 14 has a recess formed therein 75 closed by a cap 15 through which projects a pin 16 being tensioned as at 17 and being inwardly projected, the inner end of the pin 16 as shown in Fig. 5 being received in a socket 18 formed in the adjacent curved 80 portion of the handle 11. It will be seen by reference to Figs. 1 and 5, that the guard 12, positioned as shown, is so retained by the tensioned pin 16. When it is desired to 85 reverse the position of the guard, the pin 16 is moved outwardly against the tension of the spring 17 to free the inner end of the pin from the socket 18 in the sword handle 11, at which time the guard 12 may be readily shifted to its lowered position as shown 90 by dotted lines in said figures, and so retained by the tensioned pin engaging in the opposite corresponding socket 18. The pistol structure is supported by the sword 95 blade 10 adjacent the handle 11 and guard 12, and includes in detail a bracket arm 19 bifurcated at its lower end as shown in Fig. 3 to straddle the upper side of the sword blade 10 and be retained in such position by the bolt 20. The upper end of the bracket 100 arm 19 is similarly constructed and is adapted to receive a frame portion 21 of a gun barrel 22 and pivotally support the same upon the pin 23, the gun barrel 22 carrying the usual revolving shell chamber 24 co-operating 105 with an ordinary form of revolver frame 25. As shown in Figs. 2 and 4, the revolver frame has a plate 26 depending therefrom and bifurcated at its lower end, similarly to the bracket arm 19 to be received on the 110

upper edge of the sword blade 10 and so retained by the bolt 27.

From the above detailed description of the invention it is thought that the construction and operation will be at once apparent, it being noted that when the device is to be used as a sword, the guard 12 may remain in the full line position shown in Fig. 1, positioned above the handle and sword blade properly to protect the hand of the user. When it is desired to use the pistol portion of the device, the guard 12 is shifted upon its mounting rings 13 and 14 and moved to the dotted line positions shown in Figs. 1 and 5 and so retained by the tensioned locking pin 16. When so arranged, the pistol stock 25 may be readily grasped by the hand of the user and the guard 12 will be entirely removed out of the way so as to offer no hindrance whatever. As shown in dotted lines in Fig. 1 the pistol barrel 22 may be readily broken down to remove the empty shells from the shell chamber 24 and subsequently returned to proper position.

While the form of the invention herein shown and described is what is believed to be the preferred embodiment thereof, it is nevertheless to be understood that various forms, modifications and arrangements of the parts may be made without departing from the spirit and scope of the invention as claimed.

What I claim as new is:—

35 1. A combined pistol and sword including a sword blade, a handle carried thereby, a guard for the handle and a pistol attached to the sword blade adjacent the handle, the barrel of the pistol being pivotally supported.

40 2. A combined pistol and sword including a sword blade, a handle carried thereby, a guard for the handle and a pistol attached to the sword blade adjacent the handle, a bracket carried by the sword blade for pivotally supporting the barrel portion of the pistol.

45 3. A combined pistol and sword includ-

ing a sword blade, a handle carried thereby, a guard for the handle and a pistol attached to the sword blade adjacent the handle, the guard being movable relative to the sword handle and pistol.

4. A combined pistol and sword including a sword blade, a handle carried thereby, a guard for the handle and a pistol attached to the sword blade adjacent the handle, the guard being of substantial U-shape and having a ring at each end thereof rotatably supported by the sword handle.

5. A combined pistol and sword including a sword blade, a handle carried thereby, a guard for the handle and a pistol attached to the sword blade adjacent the handle, said guard being movable relative to the handle, and a tensioned pin associated with the sword handle and guard for holding the guard in adjustable position.

6. A combined pistol and sword including a sword blade, a handle carried thereby, a guard for the handle and a pistol attached to the sword blade adjacent the handle, the guard being adjustable relative to the sword handle, and a tensioned pin carried by the guard adapted to engage recesses formed in the sword handle at selective points.

7. A combined sword and pistol including a sword blade, handle and guard, a pistol supported by the sword blade adjacent the guard with the stock of the pistol in normal alinement with the guard, the guard being movable to a position remote from the pistol stock to permit an easy grasping of the pistol stock.

8. A combined sword and pistol including a sword blade, handle and guard, a pistol supported by the sword blade adjacent the guard with the stock of the pistol in normal alinement with the guard, the guard being movable to a position remote from the pistol stock to permit an easy grasping of the pistol stock, and means for holding the guard in adjusted position.

In testimony whereof I affix my signature.

JOE J. WIGIERT.
